UNITED STATES PATENT OFFICE.

GEORGE F. STICKNEY, OF ALBANY, NEW YORK.

MOVABLE CREST FOR DAMS.

989,079.

Specification of Letters Patent. Patented Apr. 11, 1911.

Application filed November 1, 1910. Serial No. 590,169.

To all whom it may concern:

Be it known that I, GEORGE F. STICKNEY, a citizen of the United States of America, residing at 28 Lancaster street, in the city 5 of Albany, in the county of Albany and State of New York, have invented certain new and useful Improvements in Movable Crests for Dams, of which the following is a specification.

10 My invention relates to movable crests for dams, and the object of my invention is to provide an automatic device for increasing the head at dams and the depth of navigable streams; for enlarging the 15 capacity of storage reservoirs; for use as a regulating device, a waste gate, etc., together with such elements and combinations as are hereinafter more particularly described and claimed. I accomplish these 20 objects by means of the mechanism illustrated in the accompanying drawing, in which:

Figure 1 is an elevation, with parts in section, of my invention when the crest is 25 raised. Fig. 2 is an elevation, with parts in section, being the same view shown in Fig. 1, with the exception that the crest is lowered and the water is at flood.

Similar letters refer to similar parts 30 throughout the several views.

The stationary substructure, A, may be built of masonry, timber or other suitable material and forms the lower part of the dam. The movable portion or crest, B, is 35 attached by hinges, C, to suitable supports, D, raised above the base, A, so that the crest, B, may rotate about a horizontal axis through an angle of sufficient amplitude to raise and depress the crest. The upper 40 part, E, of the base, A, is concave, the surface being curved to conform to the path of the outer edge of the crest, B, as it rotates about its axis with just sufficient clearance for easy operation without permitting an 45 excessive leakage of water between the two members.

The movable portion or crest, B, may be built of steel, timber or other suitable material and consists of two connected leaves, F 50 and G, placed at an angle to each other, preferably, though not necessarily, of 90°, joining horizontally at the axis of the hinges, C, by which the crest is attached to the fixed portion, D, and the leaves are 55 held rigidly in their proper position relative to each other, by ties, braces, etc., H.

The leaves are preferably, though not necessarily, plane surfaces. The upper leaf, F, is of greater area than the lower one. This difference in area may be secured by making 60 the upper leaf wider than the lower leaf and keeping the length of the leaves equal, or the upper leaf may be made longer than the lower leaf, the first arrangement being the preferable one. 65

The water, J, at the upstream side of the dam has free access to the two leaves of the crest, which latter is operated by this water pressure. The water pressures against the two leaves act in opposition 70 to each other. As the depth of water above the leaves varies the intensity of pressure varies and the forces tending to rotate the leaves varies, making the upward or the downward rotating forces preponderate according to the level of the water surface 75 above the dam. A counterweight, K, may be attached to the crest, B, so as to supplement the downward rotating forces and make the crest more sensitive, thus causing 80 it to fall at a lower stage of the water surface than if it depended upon the water pressure alone. The chains, L, attached to the leaf, F, and to the base, A, or other suitable device, are provided to limit the upward rotation of the crest, B, and a pipe or roller, M, is provided between the end of the leaf, G, of the crest and the concave surface, E, of the base, A, to prevent excessive leakage of water through the joint 85 between the two members. The roller or pipe, M, is retained in position by means of the angle plate, P, attached to the leaf, G, permitting the roller, M, to move freely between the surface of the leaf, G, and the 90 angle plate, P, and rotated also in contact with the concave surface, E, of the base, A. 95

In the side walls, N, at the ends of the dam, I place suitable pipes or conduits, O, to admit air under the leaf, F, of the crest, B, in its lowered position when water is flowing over the dam. The flow of water over the crest will exhaust the air from beneath the leaf, F, when the leaf, F, is down in the position shown in Fig. 2, creating a partial 100 vacuum which would interfere with raising the crest. The air pipes, O, in the side walls, N, will supply air to replace that carried away by the flowing water and will 105 equalize the air pressure on the two sides of the upper leaf, F. The fact that the water surface of a stream fluctuates considerably 110

at different seasons of the year, depending upon the volume of flow, makes necessary a movable dam in order to derive the greatest benefit from the stream.

5 During the dry summer months when the flow is a minimum, the water is at its lowest level and may be down to the crest of the dam or even lower. During the wet months when the flow is a maximum, the water 10 pours over the dam several feet deep as shown by full lines in Fig. 2, the dotted lines in Fig. 2 showing the water of the height of the crest, and the height of the dam is limited by the necessity of keeping 15 the high water level down to a stage that will not overflow the banks or cause damage. A fixed dam is necessarily lower than a movable dam for the reasons stated above. High water occurs but a few times in a year 20 and the flood periods are of comparatively short duration. A low dam in time of flood changing to a high dam when the flood has passed is an ideal structure for the water user as it gives the maximum head and 25 storage. My invention will effect these changes in the height of a dam, will raise the low water level and will reduce the fluctuation of the water surface without increasing the flood height.

30 What I claim as my invention and desire to secure by Letters Patent, is:

1. In a device for increasing the head at

dams, the combination of a stationary substructure; a movable crest, comprising two connecting leaves placed at an angle to each other; a means for tying said leaves rigidly in position relative to each other; a means for rotatively supporting said crest above said stationary substructure; a means for limiting the movement of said crest; and a 35 means placed in contact with said substructure and one of the leaves of the crest for decreasing the leakage between the leaf of the crest and the substructure.

2. In a device for increasing the head at 45 dams, the combination of a stationary substructure; a movable crest, comprising two connecting leaves placed at an angle to each other; a means for tying said leaves rigidly in position relative to each other; a means 50 for rotatively supporting said crest above said stationary substructure; a means for limiting the movement of said crest; a means placed in contact with said substructure and one of the leaves of the crest for decreasing 55 the leakage between the leaf of the crest and the substructure; and a counterweight attached to one of said leaves.

In testimony whereof I have affixed my signature in presence of two witnesses.

GEORGE F. STICKNEY.
